US00D819743S

(12) **United States Design Patent** (10) **Patent No.:** **US D819,743 S**
(45) **Date of Patent:** **** Jun. 5, 2018**

(54) **VERTICAL DIGITAL VIDEO BLADE**

(71) Applicant: **Americhip, Inc.**, Gardena, CA (US)

(72) Inventors: **Timothy P Clegg**, Chagrin Falls, OH (US); **Anthony V Roberts**, Rolling Hills Estates, CA (US); **Kevin C Clegg**, Redondo Beach, CA (US)

(73) Assignee: **Americhip, Inc.**, Gardena, CA (US)

(***) Term: **15 Years**

(21) Appl. No.: **29/609,527**

(22) Filed: **Jun. 30, 2017**

(57) **CLAIM**

The ornamental design for a vertical digital video blade, as shown and described.

DESCRIPTION

FIG. 1 is a perspective view of the front, top and left side of the present invention showing our new design.

FIG. 2 is a front elevational view of the present invention.

FIG. 3 is a rear elevational view of the present invention.

FIG. 4 is a right side elevational view of the present invention.

FIG. 5 is a left side elevational view of the present invention.

FIG. 6 is a top plan view of the present invention; and,

FIG. 7 is a bottom plan view of the present invention.

The shading shown in the drawings illustrate portions of the vertical digital video blade in which the design is embodied that form no part of the claimed design.

1 Claim, 3 Drawing Sheets
